[57] ABSTRACT

The columns of a switch matrix are interrogated by non-overlapping strobe pulses and the rows provide identifiable output data. Some of the switches are voting point switches whereas others are voting official switches or security switches. The data is processed by logic means which outputs data on rows corresponding to the rows of the switch matrix. The strobes and output data are fed to an indicator light matrix during vote selection and to a counter matrix during a register mode initiated by the voter. Preferably the processing is done by an arithmetic processor having a read only memory encoded with the ballot format.

SUBROUTINE

ELECTRONIC VOTING MACHINE

BACKGROUND OF THE INVENTION

This invention relates to electronic voting systems. In the past there have been a number of systems developed wherein electro-mechanical and in some cases electronic arrangements were used to perform the functions of mechanical voting machines. For the large part these systems did not meet with commercial success principally because they not only tended to be expensive to manufacture but also did not exhibit a sufficiently high degree of reliability. Mechanical voting machines have been highly developed and their manufacturing techniques perfected to an extent that they are highly reliable and inexpensive. They are rarely subject to failure in service and, moreover, are readily programmable to respond properly to different ballot formats and voting techniques which they may be called upon to perform. For example, a given machine may be used at times to register primary election voting and, at other times, to provide the distinctly different functions of general election voting, to name but two different general ballot formats which may be accommodated by a given machine.

The reliability and cost of electronic components contemporarily available is such as offers the distinct possibility for providing electronic voting machines which will rival mechanical machines in cost and reliability. Moreover, electronic machines should be capable of substantially reducing the bulk and weight of a voting machine as compared with the rather sizable figures of these factors which are common for mechanical voting machines.

Voting processes essentially are logic functions and of course respond well to the usual techniques employed electronically to perform the corresponding logic. However, if an electronic system is called upon to perform the many and different logic functions performed by an ordinary mechanical voting machine, enormous complexity ensues which immediately is reflected in high cost. Considering the enormous mechanical complexity and redundancy of mechanical voting machines, a corresponding or even greater complexity and redundancy of an electronic counterpart is not surprising and, indeed, such usually has been the case with prior electronic or electro-mechanical machines which utilize conventional techniques for converting the mechanical logic functions to corresponding electronic logic functions.

BRIEF SUMMARY OF THE INVENTION

It is accordingly a primary object of this invention to provide an electronic voting machine system which is highly reliable and is economically competitive with mechanical voting machines of comparable functionality but utilizing arrangements for performing the requisite logic which are totally different from prior systems.

Basically, the present invention is concerned with an electronic voting machine system which incorporates a voting panel divided into a number of discrete areas or voting points within the framework of which selected ballot formats may be established. Associated with each voting point is a vote selection switch and an indicator preferably in the form of a light which is energized in response to associated switch actuation. The voting machine also includes provision for tallying or

counting the votes cast for each candidate on the ballot. On or adjacent the voting panel there is also a voter exit switch and, remote from the panel so as to be under the control of an election official there is a vote enable switch. The several switches, the indicator means and the counter means each are arranged in matrix form and are associated with logic means activated by the switch matrix to actuate the indicators corresponding to voting point switches selected by the voter and when a proper selection format has been made and the voter has actuated an exit button to actuate the corresponding counter means. A clock system cyclically interrogates the switch matrix and also controls the indicator and counter matrices so as to obtain correspondence between the signals emanating from the switch matrix and the logic signals controlling the indicator and counter matrices.

The logic system performs the necessary voting logic and, as well, incorporates various security functions related to proper operation of the voting procedure. Among other things, there is provision for security or interlocks to assure that the voting machine is properly set up at the beginning of the voting day so that falsification or error in voting results cannot occur and provision is made to ensure that each voter is permitted to make that combination of selections which is allowed, i.e., overvoting is not permitted. As for undervoting, provision is made both at the voting panel and at the official's console to indicate to both the voter and to the official that the voter has not completed his choices, i.e., has undervoted.

Among the security interlocks provided is an interlock system associated with a vote tally print-out system. An adder-printer device is assured of being zeroed at the beginning of the voting day and print-out cannot be effected until the machine is shut down. When the machine is shut down, it cannot be reopened except by special manipulations performed by the proper official.

In essence, the system of this invention involves a switch matrix which encompasses not only all of the voter selection switches at the voting points of the machine, but also other switches as well. These other switches include a switch controlled by a voting official to give "entrance" to the machine, an "exit" switch at the voting machine which when actuated by the voter causes his vote selections, if proper within the ballot format, to be recorded. These other switches also include security or status switches incidental to proper operation of the system as, for example, switches which are actuated to proper condition only if the machine has been properly prepared for voting. Additionally, these other switches may include a switch which in effect changes the ballot format as, for example, by restricting the format to a portion only of the ballot format which otherwise may be achieved.

The switch matrix presents a number of input lines and a number of output lines corresponding to the columns and rows of the matrix. A logic means or processing unit is associated with these input and output lines to perform the functions of interrogating (i.e., strobing) the input lines and of processing the data from the output lines. Because of the matrix format of the switches, each is uniquely defined according to strobe time and output line identification. The processing unit acts upon the data from the switch matrix and determines the propriety of such in accord with various se-

surity interlocks or conditions and within the framework of a proper vote format. This function occurs during a "select" mode of the system and if all conditions are proper, the machine may then proceed to a "Register" mode once the voter "exits" from the machine. During the "Register" mode, the voter's selections are stored for subsequent tally.

The system herein is characterized by a counter matrix corresponding to the voting point switches, the input lines (matrix row or column) of which are strobed in consonance with the strobing of the corresponding input lines of the voting point switches and the other lines of which (matrix column or row) are enabled in consonance with the selected output lines of the voting switch matrix thereby uniquely to identify and actuate the proper counters in accord with the voter's selections.

An indicator light matrix is also used which includes not only an indicator at each voting point but also indicators to inform the voter that the machine is ready to accept his vote, an indicator to inform the voter that his vote has been recorded (when the voter "exits") and other lights which inform the voting official of proper voting procedure performed by the voter. The indicator light matrix also is strobed and actuated similarly to the counter matrix.

The system also incorporates a "Wait" mode during which power to the light matrix is off.

The periodic strobing of indicator lights is especially useful in allowing the strobe pulses to overdrive the lights, but with low duty cycle so that although the lights remain incandescent their power consumption is low. The system is such that the various official-controlled and voter-controlled switches require only momentary actuation and do not require to be reset when a vote is completed and the machine is readied for the next voter. The official-controlled "Entrance" switch causes the power to go "up" to the light matrix and initiates the transition from "Wait" to "Select" mode.

Another feature of the invention is the provision for programming the machine according to voting point switch orientation. Each voting point switch has at least two program positions which select the category for which the switch is used. Thus, each switch when in one position programs the switch for selection of a presidential candidate and in another position for selection of a congressional candidate.

BRIEF DESCRIPTION OF THE DRAWING FIGURES

FIG. 33 is the flow chart for the subroutine 100 Ms delay which is initiated during the Register mode, FIGS. 31A and 31B.

DETAILED DESCRIPTION OF THE INVENTION

Reference to FIG. 1 will reveal certain basic concepts according to the present invention. As illustrated in FIG. 1, a switch matrix indicated generally by the reference character 10 includes a plurality of input lines indicated by reference characters 12, 14, 16 and 18 and includes also a plurality of output lines 20, 22 and 24.

It will be appreciated that the number of input and output lines is not material according to the aspects of this invention and; indeed, each can be of any number. For the purpose of clarity, as will be apparent more readily hereinafter, there are however four input lines and three output lines in the illustrative embodiment of FIG. 1.

As stated, the arrangement 10 is a switch matrix and these switches are of the normally open type, one being located at as many of the cross points of the matrix as is necessary to accommodate the total number of required switches. In regard to this, the switch matrix is principally made up of a plurality of vote selection switches which are located at the voting points on a voting panel of a voting machine and these switches, in essence, form a subsidiary matrix in and of themselves within the framework of the larger number of switches required in the entire matrix to perform the necessary operations hereinafter described.

The matrix 10 also contains other switches which are not assigned to the vote selection process but which are necessary to perform subsidiary functions. For example, there is included in this additional of the matrix 10 a voter entrance switch which is under the control of an election official which performs the function of preventing operation of the voting machine until the official has given "entrance" to the machine. Also contained in this additional portion of the matrix 10 are various status or security switches and, in addition, a switch accessible to the voter which is to be actuated at the end of the voting selection to allow the voter to "exit" from the machine and which is responsible for recording the votes which he has selected.

Associated with the matrix 10 is a clock means indicated generally by the reference character 26 which has a plurality of non-overlapping phases which sequentially and cyclically are applied to the input lines 12, 14, 16 and 18 so as sequentially and cyclically to interrogate the cross points of the matrix 10. For purposes which will appear hereinafter, at least one of the input lines 12, 14, 16 and 20 is reserved for certain functions of the system and this line is devoid of any connection to vote selection switches and is interrogated in each cycle of the clock means 26 later than the interrogations of those input lines which are connected to the vote selection switches.

In any event, the selection of switches in the matrix 10 are uniquely identified at the output lines 20, 22 and 24 and are applied to the logic means indicated generally by the reference character 28. The logic means receive the vote selection information as well as status or security information and stores same for control of indicating means indicated generally by the reference character 30 and then later, to control the counting means indicated generally by the reference character 32.

Essentially, the logic means 28 has three modes of operation; a "wait" mode, a "select" mode and a "register" mode. In the "wait" mode, neither the indicator means nor the counter means is activated; in the "select" mode the indicator means is activated and in the "register" mode, the counter means is actuated.

During the select mode, the logic means 28 produces at its output lines 34, 36 and 38 information corresponding to that on the lines 20, 22 and 24 and applies such information to the indicator means 30. The indicator means 30 is of matrix form and has first input

lines 40, 42, 44 and 46 corresponding to the interrogation phases of the clock means 26 so that the indicator matrix has its cross points activated in consonance with the corresponding vote selection switches previously actuated in the matrix 10. The indicator matrix 30 includes an indicator for and corresponding to each of the voting points and associated vote selection switches of the matrix 10 and as well may contain additional indicators associated for example with the voter entrance switch previously or other security or status switches contained in the matrix 10. It will be understood that the indicators corresponding to the vote selection switches are located physically on the voting panel at the voting points to which the vote selection switches correspond so as to apprise the voter that he has made to corresponding selection.

As soon as the voter has completed his voting selection and desired to exit from the machine and thereby to record his vote, he presses the voter exit switch in the matrix 10 which transfers the vote selection information stored in the logic means 28 to the output lines 48, 50 and 52 which form input lines to the counter means 52. The counter means 52 is also in the form of a matrix of counters, one for each of the voting points of the matrix 10 and may contain also additional counters as hereinafter described. The other input lines to the counter matrix 32 are at 54, 56, 58 and 60 and are in consonance with the corresponding phases of the clock means 26, as indicated. As noted previously, the input line from the clock means 26 to the switch matrix 10 which is associated with the voter exit switch is interrogated late or last in the cycle and when this information is applied to the logic means 28, the transfer from the select to the register mode is made and such information also causes the vote information to appear for one complete cycle at the output lines 48, 50 and 52 and to reset the logic means 28 ultimately to cycle it to the wait mode. In this way, the voter entrance switch must again be actuated before another voting cycle can be effected.

Certain features will be evident from FIG. 1 even though the Figure illustrates a system in extremely simplified form. For example, it will be noted that the combination of the switch matrix 10 and likewise of indicator and counter matrices 30 and 32 all controlled directly or indirectly from a common clock means 26 in association with logic means 28 which stores the vote selection information and transfers it either to the indicator means or the counter means constitutes an arrangement which inherently minimizes the connections and interconnections required and in general provides an extremely simple and uncomplicated system for performing many and diverse voting formats. For example, the logic means 28 may include an N of M logic means which allows the voter to select N of M possible selections. If the voter selects more than N selections, he may be apprised of this fact by cancellation of all of the previous selections which is manifested by deactivation of all previously selected indicator means. The logic means 28 may also contain provision under these circumstances or any others in which the voter exit switch is ineffective to transfer the vote information from the logic means to the counter means 32 unless the voter has made the total number of selections possible. In other words, undervoting and overvoting cannot be made in the two situations generally described for such acts will not allow the counter means 32 to be actuated.

Provision ordinarily will be made for apprising the voting official of these and other voter errors or malfunctions so that the voter may be apprised of the fact that he has in fact not so voted as to cause recordation of his vote on the counter means 32.

In order to better understand the concepts above described, in conjunction with the various matrices, the clock means and the logic means, reference is had to FIG. 2. In FIG. 2, the clock means 62 is shown as having four non-overlapping phases appearing sequentially and cyclically at the output lines 64, 66, 68 and 70 which respectively control the several switches 72, 74, 76 and 78 sequentially and cyclically to connect the interrogating lines 80, 82, 84 and 86 to the terminal 88 which is connected to a source of votage as indicated. The switch matrix includes the vote selection switches 86, 88, 90, 92, 94, 96, 98, 100 and 102 and, as well, a voter entrance switch 104 located remote from the voting panel at which the vote selection switches are located and incorporated in an election official's console as indicated by the dashed lined block C. FIG. 2 shows further a voter exit switch 106 which is associated with the voting panel which defines the voting points at which the vote selection switches are located. It will be noted that the various switches are located at cross points of the matrix defined by the input line columns 80, 82, 84 and 86 and the output rows defined by the output lines 108, 110 and 112. The interrogating lines are also connected to respective parallel arrangements of indicator lights and counters so as to form the indicating means matrix and the counter means matrix as previously described.

For example, the indicator lamps are indicated by blocks labeled "L" and the counters are indicated by boxes labeled "C." The indicator lamps corresponding to the vote selection switches are located adjacent thereto at the respective voting points so that the indicator lamp 114 corresponds to the vote selection switch 86, the lamp 116 corresponds to the vote selection switch 92, the indicator 118 corresponds to the vote selection switch 98 and so on for the remaining lamps 120, 122, 124, 126, 128 and 130. The lamp 132 corresponds to the vote enable or voter entrance switch 104 and is located likewise at the election official's console C.

Lastly, the lamp 134 corresponds to the voter exit switch 106 and is located adjacent thereto at or on the voting panel which contains the vote selection switches previously described.

The counter matrix incorporates a counter associated with each voting point switch and, as well, a counter for indicating the total number of voters which have used the machine. Thus, the counter 136 corresponds to the voting point switch 86 and the indicator lamp 114, the counter 138 corresponds to the vote selection switch 92 and the corresponding indicator lamp 116 and so on for the remaining counters 140, 142, 144, 146, 148, 150 and 152 which make the remaining portion of the matrix involved with the candidates assigned to the various voting points. Additionally, the counter 154 is incorporated in the counter matrix and its function is to register the total number of voters which have used the machine.

The logic means 156 is indicated to perform N of M logic and mode logic and, as before, stores such logic and sequentially and cyclically outputs such logic on the output lines 158, 160 and 162 thereof in conso-

nance with the information and data obtained through the input lines 108, 110 and 112 when the logic system is in the select mode. When in the select mode, the select output line 164 is energized to enable the several gates 166, 168 and 170 thereby sequentially and cyclically to complete the circuits through the indicator matrix through the lines 172, 174 and 176. Thus, the appropriate indicator lamps are intermittently energized whenever one of the switches 72, 74, 76 or 78 and simultaneously one of the switches 166, 168 or 170 is energized. Thus, once a vote selection switch has been energized momentarily, its associated indicator lamp thereafter will be energized. For this purpose, it is preferred that the indicator lamps be 4.5 volt lamps and that the voltage input at the terminal 88 be in the order of 15 volts so as intermittently to overdrive these lamps in such fashion as produces a useful output therefrom without exceeding a normal current draw throughout.

The logic means 156 responds to reset itself whenever a voter overvotes the allowed number of vote point switches, thereby extinguishing all indicator lamps apprising the voter that he has in fact overvoted. Assuming that the voter has made the proper and legal number of selections, he may then actuate the voter exit switch 106 momentarily thereby to input this information to the logic means through the line 110. The phases of the clocks 62 are non-overlapping and that applied to the switch 78 occurs later in each cycle than those phases which are applied to the voting point selection switches so that, in cycle time, the voter exit information occurs later than the latest information from the vote selection switches. The logic circuitry 156 responds to actuation of the voter exit switch 106 to shut off the select mode output at the line 164 thereby to disable all of the gates 166, 168 and 170 and to energize or actuate the register mode output line 180 thereby to enable the register mode gates 182, 184 and 186 thus sequentially energizing the lines 188, 190 and 192 and, at the end of the cycle, corresponding to the input from the voter exit switch 106, the logic means responds by resetting itself to zero and setting itself from the register mode to the wait mode. As a consequence, one cycle of information is outputted at the lines 188, 190 and 192 to actuate the corresponding counters of the counter matrix and thereby step them forward by a vote of one in each instance.

FIGS. 1 and 2 illustrate well one of the important features according to the present invention, namely, that of providing an arrangement wherein logic means is uniquely related to a clock system and matrices of switches, indicators and counters wherein the interconnections between the matrices and the logic means is standardized. In this way, it is possible to accommodate for any desired ballot format and any desired voting process simply by setting up the logic means to perform the requisite functions. The remainder of the machine is standard and remains the same in any case. In practical terms, this means that the logic means can be accommodated, for example, on a circuit card or sets of circuit cards wherein simply replacing them by another card or set of cards one can change the logic function performed within the desired ballot format. It is further possible to perform the entire logic function within a single minicomputer composed of a semi-conductor chip in which case the simple replacement of one chip by another will correspondingly change the logic func-

tions in the desired manner. Thus, the machine in large part may be composed of standard components as, for example, an ADDO-X COUNTER-PRINTER which, in conjunction with its moveable platen allows print out of the voting tally at the end of the voting day. Such an arrangement also allows certain status or security interlocking to be incorporated as, for example, interlocks from the position of the platen and from the normal officials' keys utilized in conjunction with the machines.

To illustrate a further aspect of the present invention made possible by the above general overall arrangement, reference is had at this time to FIG. 3. In FIG. 3, a clock means 200 is provided, having, again, a plurality of output phases which are non-overlapping and which appear sequentially and cyclically at the output lines 202, 204, 206 and 208. These clock outputs are applied to the switch matrix 210 and, as well, to the indicator matrix 212 and to the counter matrix 214. The switch matrix in this case, however, incorporates two sets of output lines as indicated by reference characters 216, 218, 220 and 222, 224, 226. The vote selection switches may be associated with either one of each pair of output lines such as the pair 216, 222 simply by position or orientation of the associated voting switch. This is indicated in FIG. 3 for the two switches 228 and 230.

As shown, these two switches are orientated 180° with respect to each other, the switch 228 being effective to bridge between the input line 202 and the output line 216 whereas the switch 230 is shown as bridging between the same input line 202 and the output line 224 of the other set of output lines as compared with the output line to which the switch 228 is connected. In the specific case shown in the illustrative embodiment of FIG. 3, the voting functions to be performed are selection of one from many possibilities of presidential candidates and one from many possible congressional candidates, the logic functions for these being performed respectively by the logic means 232 and 234. Thus, the vote selection switch 228 would be associated with a possible presidential candidate and the voting selection switch 230 would be associated with a congressional candidate. Thus, an additional programming function is achieved simply by orientation of the vote selection switches and a preferred embodiment of this relationship is described hereinafter in detail. It should be understood, however, that the orientation of vote selection switches need not be limited to two as is shown in FIG. 3 but there may be a great number of possible orientations of each voter selection switch to effect a requisite and desired programming function.

Insofar as FIG. 3, is concerned, the remainder of the operation is generally in accord with the descriptions presented above with respect to FIGS. 1 and 2. That is to say, during the select mode of operation, the output lines 236, 238, and 240 of the presidential logic means 232 and the output lines 242, 244 and 246 of the congressional logic means 234 are applied to the indicator matrix 212. It will be noted that these output lines are tied together as shown because each orientation of a switch excludes mutually the other or any other orientation thereof and no ambiguity can result.

Likewise, in the register mode the vote information data is cycled out of the presidential logic means 232 at the output lines 248, 250 and 252 and out of the con-

gressional logic means 234 at the output lines 254, 256 and 258 correspondingly to actuate the requisite counters of the counter matrix 214.

Certain principles of the invention have been set forth with reference to FIGS. 1-3 inclusive above whereas a preferred type of voting machine system is shown in FIG. 4. In FIG. 4, three matrices are shown, the switch matrix 260, the indicator matrix 262 and the counter matrix 264. The switch matrix 260 contains not only all of the voting switches associated with the voting points of the voting panel of the machine, but also remote control switches under the control of the voting official or officials and includes security switches for the voting machine. The indicator matrix 262 includes indicator lights not only for each voting point of the voting panel but also includes lights associated with the control panel under the control of the election official or officials as well as information-giving lights at the voting panel such as a "start vote" and a "vote complete" light. The counter matrix includes not only a counter for each voting point but may include other counters as well such as a counter which indicates the total of all votes cast and a counter which totals the number of voters which have used the machine on any given voting day.

The logic or processing is performed by the unit 266 and which produces a repetitive sequence of strobe or clock phase signals at the lines 268, 270, 272, 274, 276 and 278 which correspondingly strobe the input columns 280 of the switch matrix 260, the input columns 282 of the indicator matrix 262 and the input columns 282 of the counter matrix 264. Dependent upon proper voting conditions and a voting sequence or format selected by the voter at the voting panel by actuation of the switches thereof within the matrix 260, the strobe signals are passed through the corresponding row or rows of the output rows 284 of the switch matrix. In mode 1 these output signals from the switch matrix are enabled by the mode signal at the line 286 and are passed to the corresponding input rows 288 of the indicator matrix 262 over the multiple connections 290. The processing unit 266 determines the correctness of the voting conditions and of the vote inputs and if everything is correct and the voter depresses a "vote complete" switch in the matrix 260, the processing unit 266 responds by enabling the counter matrix 264 over the conductor 292 so that the input rows 294 thereof are capable of actuating the requisite and proper counters of the matrix 264 in accord with the signals appearing at the input columns 282 and the input rows 294.

In preferred embodiments of the invention as shown in accord with FIG. 4, the processing unit 266 shuts down the power to the light matrix of the machine 10 seconds after completion of the tabulation and power to the light matrix is not initiated until a voting official gives entrance to the machine by depressing a "voter entrance" switch within the matrix 260.

An illustrative embodiment of the system according to FIG. 4 is shown in FIGS. 5-16 inclusive to which reference is now had.

With reference first particularly to FIG. 5, in the voting machine system shown therein, the switch, indicator light and counter matrices are indicated by the block 300 and the processing unit includes the presidential register unit 302, the clock 304, the congressional candidate register 306, the presidential register gate

unit 308, the select logic unit 310, the congressional register gate unit 312, the presidential control logic unit 314, the congressional control logic unit 316, the status register unit 318, and the status logic unit 320.

For the system shown, there are 48 voting points any one of which may be programmed by the associated voting point switch to register either a presidential or a congressional candidate and the ballot format is that the voter may vote for one and only one presidential candidate and one and only one congressional candidate or, alternatively, a single category ballot format is permitted, in which only one candidate may be selected from the entire ballot. There are eight input rows to the matrix unit 300 and six output columns each for presidential and congressional candidates in accord with the programmed position of the voting point switches. There are three modes of operation, a "select" mode designated as mode 1, a "register" mode designated as mode 2 and a "wait" mode designated as mode 3 during all of which the clock of FIG. 7 is operating. In the "wait" mode, the power is down to the light matrix and when the voting official gives entrance to the machine, the power goes up to the light matrix. At the beginning of the voting day, the clock unit 304 is reset and a corresponding reset signal is applied at the conductor 322 to the status logic unit 320. The status logic unit generates the signals providing the logic inputs for modes 1 and 3 and initiates mode 2 by a start mode 2 signal at the conductor 324 applied to the clock unit 304 which then provides a correctly phased mode 2 signal. The outputs of the clock unit 304 are the master clock signal at the conductor 326, the inverse of the master clock signal at the conductor 328, a phase 2 signal at the conductor 330, a phase 2 inverted signal at the conductor 332, an inverted phase 3 signal at the conductor 334, a phase 4 signal at the conductor 336, a mode 2 signal at the conductor 338, an inverted mode 2 signal at the conductor 340, nine clock strobes at the conductors 342 and the inverse of these strobes at the conductors 344. From the clock unit 304, eight strobe pulses sequentially are applied to the SLC matrix unit 300 as indicated by the conductors 346 and the row outputs corresponding to these strobing pulses appear at the multiple conductors 348 for the congressional candidates and at the plural conductors 350 for the presidential candidates. These row outputs are applied to the congressional register 306 and the presidential register 302 as indicated.

Inverted outputs corresponding to the row inputs to the presidential register unit 302 appear at the multiple conductors 360 and from there are applied to the presidential register gate unit 308 as shown. Correspondingly, strobe pulses A-H corresponding to input columns selected at the switch matrix appear at the multiple conductors 362 and these are also applied to the P-register gates unit 308 as illustrated. For performing this latter function, strobe pulses A-H are applied to the presidential register unit 302 over the multiple conductors 364 and inverted corresponding signals are applied over the multiple conductors 366. The P-register gates unit 308 has a single output at the conductor 366 indicating that the no presidential candidate has been selected, it produces select outputs 1-6 at the multiple conductors 368 in accord with the voting taking place at the matrix unit 300 and an additional signal at the conductor 370 is generated when presidential voting

point switches are selected at two or more input columns.

Similarly, the congressional register unit 306 has congressional candidate strobe pulses appearing at the multiple conductors 380 in consonance with the selections at the matrix 300 and the multiple conductors 382 produce the corresponding strobe outputs on the rows 1-6. These signals are applied to the C register gates unit 312 to produce the inverted C NONE signal at the conductor 384 or the row output select signals at the multiple conductors 386. Likewise, the unit 312 performs the function of generating a signal at the output conductor 388 when congressional candidates are selected at two or more of the input columns. The register units 302 and 306 perform an initial function of detecting when a presidential or congressional button is stuck as indicated by signals appearing at the output conductors 390 and 392 and these signals are applied to the status logic unit 320, as shown.

20 The outputs at 366 and 368 of the P-register gates unit 308 and the outputs at 384 and 386 of the C-register gates unit 312 are applied to the select logic unit 310. In addition, the select logic unit 310 has additional inputs as follows:

- 25 1. A clock J-input at 390 which is the J-strobe from the clock unit 304,
2. An inverted status J-input at the conductor 392 which is generated in the status register unit 318, as indicated.
- 30 3. A one-presidential selection signal at the input conductor 394 also generated by the status register unit 18 as indicated.
4. A mode 1 or "select" mode input signal at the conductor 396 generated by the status logic unit 320 as shown.
5. A "wait" mode input at the conductor 398 also generated by the status logic unit 320.
6. A 10 second signal at the conductor 400 generated by the status logic unit 320.
- 40 7. A select error signal (i.e., overvote) at the input conductor 402 also generated by the status logic unit 320.

The output of the select logic unit 310 appears at the multiple conductor 404 and these inputs are applied to the matrix unit 300. It should be appreciated that the select signals at the output conductors 404 and which are applied to the matrix 300 do not exceed the ballot format possibility and they correspond to the selected rows whereas the strobes at the conductors 346 continue to provide the column inputs.

It will be appreciated that the select and register functions are effected in response to the clock J strobe, other conditions being proper. In contrast, the control logic functions performed by the units 314 and 316 respond to the clock K strobe as indicated at the inputs 410 to these two units, same emanating from the clock unit 304 as will be understood. The presidential control logic unit 314 produces an output signal at the conductor 412 when no candidate has been selected and this signal is applied to the status register unit 318. The unit 314 produces a signal at the output conductor 414 when no presidential row output has been selected and also produces outputs at the conductors 416 and 418 respectively to indicate when one presidential output row selection has been made and when two or more output rows are selected. The unit 314 also produces an output at the conductor 420 when no input column

for the presidential candidates has been selected and signals at the conductors 422 and 424 when one and, respectively two or more input columns corresponding to presidential candidates have been selected. The unit 314 also produces an output signal 426 indicating completion of the voting cycle and an inverted signal thereof is at the output conductor 428. Further, the unit 314 produces a signal at the output conductor 430 when no candidates have been selected.

The congressional control logic unit 316 provides an output at the conductor 432 when no row output has been selected for congressional candidates, a signal at the output conductor 434 when one row has been selected for the congressional candidates and an output at the conductor 436 when two or more rows have been selected in the congressional category. Additionally, the unit 316 produces the output signals at the conductors 438, 440 and 442 to indicate no column strobes selected, one column strobe selected and two or more column strobes selected respectively.

Several of the outputs of the presidential control logic unit 314 are fed back to its inputs as indicated and several of the outputs of the congressional control logic unit 316 are fed as inputs to the presidential control logic unit 314. In addition, both of the units 314 and 316 are provided with inverted strobe inputs corresponding to inverted strobes A-F, as indicated by the input lines 450 in each case.

The status register unit 314 has the following outputs in addition to those already described:

1. An output at the conductor 500 indicative that exit button or vote completion button has been depressed by the voter.
2. An output at the conductor 502 indicative that the voting official has given entrance to the machine by depressing the voter entrance button.
3. An output at the conductor 504 indicative that the platen of the machine is to the left.
4. An output at the conductor 506 indicative that the platen of the machine is to the right.
5. An output at the conductor 508 indicative that the custodian switch has been actuated at the beginning of the voting day.
6. An output at the conductor 510 indicative that the 2 key has been closed at the beginning of the election day.
7. The output at the conductor 512 which is inverse of the single category output at the conductor 392.
8. An output at the conductor 514 indicating that one congressional candidate has been selected.

An additional input not yet described for the status register unit 318 is the J clock strobe at the input conductor 516 which emanates from the clock unit 304 and is indicative that the status register responds to this J strobe.

The above description in conjunction with FIG. 5 describes the relative cooperation between the inputs and outputs of the processing unit in conjunction with the matrix system 300.

The clock unit 304 is shown in FIG. 7 and includes, in addition to the inputs and outputs previously described, the individual strobe or phase outputs at the conductors 600, 602, 604, 606, 608, 610, 612, 614, 616 and 618 and their corresponding inverted outputs at the conductors 620, 622, 624, 626, 628, 630, 632, 634, 636 and 638. The clock unit includes a 4 phase section indicated generally by the reference character

640 and a 9 phase section indicated generally by the reference character 642. Typical timing diagrams are indicated in FIG. 7a. The master oscillator is indicated by the reference character 644 and drives the 4 phase system which includes the several flip-flops 646, 648, 650 and 652 and associated gating as shown and the 9 phase clock portion of the system includes the flip-flop 654 and 656 and the counters 658, 660 and 662 and gating circuits as shown at the beginning of a voting day when the power is supplied to the machine, the charging of the capacitor 623 causes the NOR gate 664 to perform a reset function.

FIG. 6 illustrates the unit 300 of FIG. 5 in somewhat simplified form for purpose of clarity. Thus, the switch matrix indicated generally by the reference character 736 is only incompletely shown and the light matrix indicated generally by the reference character 738 is likewise incompletely shown and the counter matrix indicated generally by the reference character 740 is also incompletely shown. Nine clock phases, or strobes A-J are supplied sequentially to the Darlintons corresponding to these phase and some of which are indicated by reference characters 742, 744, 746, and 748. These Darlintons respectively correspond to the A, B, H and J strobes, as will be evident and when these strobes are negative going, their corresponding switches are on so as to connect the positive voltage supply line at 750 sequentially to the supply lines 752, 754, 756 and 758 which correspond to the aforesaid strobe or clock phases and it being understood that phases or strobes C-G inclusive have been omitted, and their corresponding circuitry also, for the purpose of clarity. Eight of these clock phases or strobes are used to strobe the voting point switches and to provide the corresponding column inputs thereto. Each switch, as has been previously described, is physically programmable to connect either with a congressional candidate output row or a presidential candidate output row, there being twelve such rows, six of which correspond to congressional candidates and six of which correspond to presidential candidates. The presidential candidate rows are indicated at 712, 714, 716, 718, 720 and 722 in FIG. 8 whereas the congressional rows are indicated by reference character 724, 726, 728, 730, 732 and 734 in FIG. 11 and certain of these are shown also in FIG. 6 as will be evident. Thus, after a switch such as the switch 760 has been depressed and a corresponding signal presented at the conductor 722 during the strobe A time, a select signal appearing at the row input conductor 710 turns on the Darlington 762, assuming that the select mode switch 764 is operative at this time thereby to pulse the indicator light 766 corresponding to the switch 760, and so on for each of the various switches. After the proper vote has been selected, and the voter presses the exit button, mode 2 will commence extinguishing the Darlington 764 and turning on the Darlington 770. Then, during the strobe A phase and with a signal appearing at the select input row 710, the Darlington 772 will be turned on thereby to energize the counter 774 corresponding to the light 766 and the switch 760.

It will be appreciated that the switch 760, when used, eliminates the switch designated by the reference character 776. In other words, each switch, being physically programmable, is either in a position corresponding to the switch 760 or in a position corresponding to the switch 776, the position of the switch 760 correspond-

ing to a presidential candidate selection whereas the position of the switch as shown at 776 corresponding to the same voting point but corresponding to a congressional candidate. Similarly, for the switches indicated by reference characters 778 and 780, and so on. For clarity, it should be mentioned that alternate switch positions are shown at 782 and 784 and, as well, at the position 786 and 788 with all of the switches 760, 776, 782, 784, 786 and 788 corresponding to those interrogated during the A phase or strobe of the clock, the alternate positions 778 and 780 being interrogated during the B strobe or clock phase whereas the third line of switches are interrogated during the H strobe or clock phase.

Associated with the J strobe are a number of switches which are not shown on FIG. 6 but which involve the official control or security of the system as will hereinafter be described more particularly. Certain lights are associated with these switches one of which is the ready light 800 which operates when the voting official has given entrance to the machine. Another light is the indicator 802 which flashes on at the official control panel or remote unit when one presidential candidate has been voted and the light 804 similarly flashes on when the voter has selected one congressional candidate. Additionally, there is button stuck light 806 and a vote complete light 808 and, additionally, three counters 810 which individually tally the presidential and congressional office votes in their totalities and the total number of voters using the machine in a particular voting day.

All of the switches in the voting point switch matrix are mounted on a common printed circuit board as are the various transistors associated therewith and the lights, as will be described hereinafter, are integrally associated with the switches with the counters being disposed in the rearward portion of the machine. In addition, there is a voting official control panel or remote panel containing certain switches as hereinafter described and the lights described hereinabove in conjunction with the J strobe or clock phase. The strobe phases A-H are associated with the switches of the voting panel switch points whereas the phase J is associated with the remote control panel. There are 10 clock phases in all and the tenth or last phase is employed for reset purposes.

It is a feature of the invention that the indicator lights are strobed only and are not continuously energized. For this purpose, the strobe pulses overdrive the illuminating lights but the duty cycle is low whereby the lights operate properly.

When the voter actuates the exit button, a 10 second timer is energized which causes the vote complete light to go on. The exit button also initiates the register mode which continues until the tally is complete and during which time the buzzer 812 sounds. As soon as the tally is complete the wait mode commences.

The presidential candidate register is shown in FIG. 8, corresponding to the unit 302 in FIG. 5 as previously noted the six column outputs of the matrix unit 300 are applied at the conductor 712, 714, 716, 718, 720 and 722 which are applied to a bank of NOR gates indicated generally by the reference character 820. These NOR gates drive flip-flop stages indicated generally by the reference character 822 which produce the presidential row outputs at the conductors 824, 826, 828, 830, 832 and 834 which correspond to the output at

360 in FIG. 5. If more than one presidential candidate has been voted for which either produces a P Many Row or a P Many CLK signal to the gate 836, the system of FIG. 8 is reset by a signal appearing at the conductor 838. As indicated by a conductor 402 the "wait" mode signal thereat also is effective to reset the system of FIG. 8. Similarly, the gate 840 is effective to reset the system of FIG. 8 if a signal appears at the reset conductor 842 which is the reset pulse for the congressional candidate register hereinafter described during a single category ballot format.

Essentially, the gates 820 and flip-flop stages 822 provide the row information corresponding to the selected switches at the voting point panel.

The clock information or column selected information is achieved by means of the banks of gates 842 and 844 and the bank of flip-flops stages as indicated by the reference character 846. The gates 842 receive one input from the strobe inputs A-H inclusive, as shown, and other inputs are enabled so long as the bank of gates 848 does not indicate that more than one row output has been selected. If only one output has been selected, one of the inputs 600-614 is passed and the flip-flop stages 846 react to produce a corresponding output at one of the lines leading to the bank of gates 850. The other input to the gates 850 are the inverted strobe signals correspondingly to produce an output at one of the conductors 852, 854, 856, 858, 860, 862, 864 and 866 which correspond to the outputs at the multiple conductor line 362 in FIG. 5. FIG. 8a illustrates a typical timing diagram for the system of FIG. 8.

The signal appearing at the output conductor 390 indicating that a presidential candidate button is stuck occurs, if, after reset, the system indicates that a presidential button has remained energized.

The row information and the clock column information outputs of the system of FIG. 8 are fed as inputs to the presidential candidate register gates section as illustrated in FIG. 9 at the left-hand side thereof. If no row information is present, the gates 900 and 902 cooperate with the gate 904 to produce an output at the conductor 366 described in conjunction with FIG. 5. This row information is also applied as inputs to the column of NAND gates 906 which are either enabled or disabled as a result of the output of the gate 908 in the bank of NAND gates 910. The gate 908 in fact acts as an inverter such that when the output of the gate 912 is up, the output of the gate 908 at 914 is down and vice versa, the output of the gate 912 being the plural clock signal at the output conductor 370 as described in conjunction with FIG. 5. The outputs of the gates 906 are inverted by the bank of inverters 916 to produce the selected presidential candidate output column information at the conductors 918, 920, 922, 924, 926 and 928 which correspond to the multiple output at the multiple conductor 368 in FIG. 5. The gates 930 and 932 perform the function in conjunction with the gate 912 of detecting when at least two presidential candidate column inputs have been selected.

The congressional candidate register shown in FIG. 11 performs a function very similar to the system of FIG. 8 except for the fact that it is associated with the congressional candidates. The bank of gates 950 in conjunction with the flip-flop stages 952 provide the row output information at the conductors 954, 956, 958, 960, 962 and 964 which were applied as inputs to

the register gates unit shown in FIG. 12 and the gate 966 in conjunction with the gate 968 provides the reset C output at 842 previously described and which is also applied to the circuit of FIG. 8. The row or clock information is provided at the output conductors 966, 968, 970, 972, 974, 976, 978 and 980 in conjunction with the clock inputs to the bank of gates 982 which drive the bank of gates 984 which are connected to the flip-flop stages 986.

The row and clock information from the unit of FIG. 11 are applied as inputs at the left-hand side of the congressional candidate register gates unit as shown in FIG. 12. This unit is identical with that shown and described in conjunction with FIG. 9 except that it applies to the congressional candidates and ultimately produces the row output information at the conductors 1000, 1002, 1004, 1006, 1008 and 1010, as shown.

The function of the system as shown in FIG. 10 is to provide certain interlock signals. For example, the presidential row information in conjunction with the clock phases is applied to a bank of gates 1050 having outputs to a bank of gates 1052 ultimately feeding the NAND gate 1054 which, in association with the inverter 1056 provides clock pulses for the decade counter 1058. This counter and the decade counter 1060 are reset at every K strobe by the signal at the conductor 618 so that for each cycle a counter 1058 counts the number of row selection signals and indicates that either no one has been selected at the conductor 414, that one has been selected at the conductor 416 and that two or more have been selected at the conductor 418. Similarly, the decade counter 1060 is strobed by the P clock inputs at the conductor 370 to indicate either that no clock pulse has been selected at the conductor 420, that one clock pulse has been selected at the conductor 422 and, at the conductor 424 that two or more clock pulses have been selected.

A portion of the unit of FIG. 10 provides a vote complete signal and an inverted signal at the conductors 426 and 428 bearing the "register" mode. The two gates 1064 and 1066 receive the one row presidential input at the conductor 416 and the one presidential clock input at the conductor 422 and the single category input at the conductor 392 such that in either the normal ballot format or in the single category format, the gate 1068 is supplied with the requisite input at 1070 such that if the one congressional row input signal is at the conductor 434 and the one congressional clock input is at the conductor 440, the output at the gate 1068 will be such as to provide the requisite vote complete and vote complete inversion output signals at the conductors 426 and 428. The gate 1070 performs the function of providing the inverted none output at the conductor 430 in response to the various none row and clock inputs at its conductors 414, 420, 432 and 438.

The congressional control candidate logic shown in FIG. 13 and corresponding to the unit 316 of FIG. 5 performs a function similar to the system of FIG. 10 although because of the single category facet of the ballot format possibility, the logic is somewhat simpler.

The select logic unit as shown in FIG. 14 corresponds to the unit 310 in FIG. 5. The inputs at the conductors 338 and 390 to the gate 1100 provide a signal, during the "register" mode which, after inversion at 1102 provides a totalizer output at the conductor 1104 which is passed by the gate 1106 and inverted at 1108 to appear

at the row 4 conductor 706 during the J strobe. This signal is applied to the totalizer of the bank 810 in FIG. 6 which totalizes the number of voters which have voted. During the "wait" mode and during the J strobe, assuming that no congressional candidates have been indicated at the conductor 384 and no presidential candidates have been indicated at the conductor 366 or, alternatively, that single category is not being used as applied to the conductor 392, the gate 1110 responds and, after inversion at 1112 produces a ready light signal at the conductor 114 which is passed by the gate 1116 and inverted as at 1118 to provide a corresponding signal on the row 3 output conductor 704.

During the "wait" mode as indicated by the presence of the mode 3 signal at the conductor 398 and during the 10 second delay after the register mode as indicated by the input to the conductor 400 and during the J strobe as indicated by the input to the conductor 390 the gate 1120 passes a signal which is inverted at 1122 to provide the vote complete signal at the conductor 1124. After being passed by the gate 1126 and inverted at 1128 the vote complete signal is applied to the 5th row output conductor 708. Also during the "wait" mode as indicated by the signal to the conductor 398 and if a select error signal is present at the conductor 402 during the J strobe as provided by the conductor 390, the gate 1130 passes a signal which is inverted at 1132 to provide a button stuck signal at the conductor 1134. This signal is passed by the gate 1136 and inverted at 1138 to be applied to the sixth row output conductor 710.

During the "select" mode or mode 1, the presidential and congressional candidate row select signals paired as indicated at 918 and 1000 at 920 and 1002, at 922 and 1004, at 924 and 1006, at 926 and 1008 and at 928 and 1010 are applied to the gates 1140, 1142, 1144, 1146, 1148 and 1150 respectively which pass either or both signals of each pair to provide the proper row output signals at the respective conductors 1152, 1154, 1156, 1158, 1160 and 1162 ultimately to appear at the proper row output as the selection signals at the conductors 700, 702, 704, 706, 708 and 710.

During the "select" mode, either the single category signal appearing at the conductor 392 or the 1P signal appearing at the conductor 394 to the gate 1170 will, during the J strobe as provided at the conductor 390, cause the gate 1172 to produce a signal at its output 1174 which, after inversion at 1178 will provide a 1P signal at the conductor 1180 for energizing the 1P light on the control panel for the election official and which signal is passed by the gate 1182 ultimately to appear at the row 1 output conductor 700 during the J strobe. Similarly, the C1 signal at the conductor 514 and the clock J signal at the conductor 390 cause the gate 1184 to provide a signal as output conductor 1186 which, after inversion at 1188 provides a signal at the conductor 1190 corresponding to one congressional candidate having been elected and which is passed by the gate 1192 and inverted at 1194 to appear at the second row output select signal conductor 702 during the J strobe. Thus, it will be seen that the J strobe is reserved for actuating the voting official control panel system.

The status register unit 318 of FIG. 5 is illustrated in FIG. 15 in detail. A number of operative status switches are provided. The status switch 1200 is the exit button at the voting panel; the status switch 1202 is the entrance button or switch at the voting official control

panel; the status switch 1204 is a switch associated with the printing platen of the voting machine; the status switch 1206 is a switch associated with the printing platen of the machine; the status switch 1208 is a custodian switch associated with the voting machine; the status switch 1210 is a 2KEY switch associated with the official control console or panel and the status switch 1212 is a single category switch. All of these switches are strobed during the J strobe as indicated by the input conductor 516. The printing mechanism functions in such a manner that when the voting machine is programmed, all counters are reset and the platen or roller carriage is stationed on the right side of the machine. In this condition, the switch 1206 is closed and its function is to advise the logic that the platen is located to the right and thereby prevents the machine from being operated. Two switches are located on the left side of the machine and are actuated by the platen when cranked to the left side prior to the voting day. One of these switches, the platen left switch 1204 normally is closed and is opened when the platen is located at the full left position and the other switch is the custodian switch 1208. The switch 1208 is normally closed during the programming and initiating sequence. However, prior to voting when the platen moves to the fully left position, the switch 1208 is opened and remains open and therefore cannot be reset except by a custodian or official with proper credentials and keys.

The entrance switch which is under control of the voting official actuates the contacts 1202 which are the entrance status switch. The switch 1202 is normally open and closes only when the entrance button is depressed. The logic is such that the entrance command can be given only if the entrance switch is moved from a non-depressed to a depressed condition.

The exit button available to the voter to complete his vote actuates the normally open switch 1200. After the voter has made two selections (one from each category) the voter depresses the exit button and closes the switch 1200 to register his vote. Actuation of this switch causes the logic to change from the select mode to the register mode. The single category switch 1212 causes the voting machine to operate in a single category mode which, in such mode, places all selector switches in equivalent condition so that exit shall be made after only one selection has been made.

From the above discussion, the operation of FIG. 15 should be evident. The status switches are connected through a bank of inverters 1220 to the bank of gates 1222 which drive the flip-flop stages 1224. The platen left and 2KEY signals at the conductors 504 and 510 are applied to the gate 1226 and inverted at 1228 for application as an input to the gate 1230 to prevent entrance to the machine until the platen is in the proper position and the 2KEY is "down." The flip-flop stages 1224 are reset through the gate 1232 upon coincidence of signals at the conductors 328 and 352. It will be remembered that the signal at the conductors 352 is generated at the switch matrix of FIG. 6 and does not emanate from the clock unit.

The bank of gates 1222 are enabled by the signals appearing at the conductor 352 and it is to be noted that the gate 1232 has a third input at the conductor 1234 from the gate 1236 which prevents an exit signal to be generated at the conductor 500 until the logic is proper at the gates 1238 and 1240. The single category switch 1212 is not gated in the same fashion as are the remain-

der of the status switches but, instead, is applied to set the flip-flop 1242 which has a reset connection from the strobe J as applied at the conductor 516.

The status logic is illustrated in FIG. 16 and corresponds to the unit 320 of FIG. 5. When the entrance button is depressed and a signal appears at the conductor 502, and assuming also that the error flip-flop 1300 is in the proper condition such that its output at 1302 which, like the signal at 502 is applied to the gate 1304 is in the proper condition, the flip-flop 1306 is set so that it is clocked during the next J strobe as applied at the conductor 516, through the gate 1308 and the gate 1310. This strobes the flip-flop 1314 and the entrance signal is given at the conductor 1316. The mode 1 signal at the conductor 396 resets the flip-flop 1340.

The initial reset signal appears at the conductor 322 at the beginning of the election day and is applied to the gate 1318 and after inversion is applied to the conductor 1320 which latter is applied to the gates 1322 and 1324 to reset the flip-flops 1306 and 1314 and also to reset the flip-flop 1326. Further, this signal is inverted at the gate 1330 and is used to reset the flip-flop 1332. After the initial reset, the flip-flop 1326 is reset in response to generation of the Mode 2 signal and coincidence with the K strobe which sets the flip-flop 1327 through the gate 1329. The flip-flop 1327 in turn sets the flip-flop 1331 which is then clocked by a K strobe and, through the gate 1333 provides the reset input to the gate 1322. Likewise after initial reset, the flip-flop 1332 is reset by the K strobe at the end of a cycle through the gate 1335.

When the exit button is depressed, the signal appears at the conductor 500 to set the flip-flop 1340 and, through the gate 1342, to set the flip-flop 1344 which is, in effect, the exit command flip-flop. This flip-flop is strobed at the proper time through the gate 1346 and the signal appearing at its output 1348 is applied to the gate 1350 to set the flip-flop 1326 which, in turn, causes the gate 1352 to respond and produce the start mode 2 signal at the output conductor 324.

The flip-flop 1354 is reset by the flip-flop 1326 and is set through the gate 1360 to produce, through the gate 1362, the Mode 3 or "wait" mode condition.

The K strobe at the conductor 410 resets the flip-flops 1300 and 1344, and when a Mode 2 signal appears at the conductor 338 to set the flip-flop 1363 the 10 second signal is initiated at the conductor 400. This signal remains up until the counters 1365, 1367 and 1369 count out K strobos ultimately to reset the flip-flop 1363. This takes approximately 10 seconds.

FIG. 17 is a perspective view showing a preferred embodiment of the invention. In this Figure, the voting machine proper is indicated generally by the reference character 1400 and will be seen to include a voting panel portion 1402 provided with the candidate selection buttons such as those indicated by the reference characters 1404 and, in addition thereto the panel is provided with the exit button 1406 and a light at the position shown at 1408 which indicates that the machine is ready for voting. Several sources of power may be utilized for the machine as, for example, by connection as at 1410 to a normal a.c. outlet; alternatively the connection may be made to external batteries 1412 through the emergency power supply cables 1414 and, internally of the machine there may be provided nickel cadmium or similar type batteries for powering the system.

The voting official console or remote unit is indicated by reference character 1416 and a length of cable 1418 connects this remote control unit to the main machine 1400. The panel 1420 of the remote control unit is provided with a light 1422 which indicates that a presidential selection has been made and a light at 1424 indicating that a congressional selection has been made. The light 1426 indicates vote completion and the light 1428 is illuminated when a button is stuck on the machine. The lock 1430 accepts the number 2KEY and controls the 2KEY switch and, in addition, there is provided a window through which a counter which tabulates the number of voters which have used the machine is exposed such window being indicated by the reference character 1432 and there is, in addition, a battery level indicator 1434 and an a.c. indicator 1436.

Storage and shipping containers are provided for each machine as indicated generally by the reference character 1438, the container being illustrated in closed condition at 1440. When enclosed in the container, the machine is essentially sealed and is provided with a humidity indicator at 1442 and also with a manually depressible pressure relief valve 1444.

A section through the machine 1400 is indicated in FIG. 18 wherein a number of the switches 1450 will be evident and these are engaged directly with the printed circuit board 1452 mounted on the main frame of the machine. Certain of the transistors 1454 associated with the printed circuit board and forming part of the switch, light and counter matrix are shown and diodes 1456 also associated with the printed circuit board and the matrix assembly are indicated at 1456. The counter coils are indicated by reference character 1458 and the counter wheel stacks are indicated at 1460. The platen assembly is indicated by the reference character 1462 and carries a number of rollers 1464 which cooperate with the counter wheel stacks 1460 to depress the intervening printer pack assembly 1466 against the wheels to print-out the tabulations thereon. When the printing pack is released, the chute 1468 allows same to be discharged from the machine.

FIG. 19 is an exploded view showing one of the selector switches and its associated indicating light assembly. The switch includes a base 1500 having mounting and connector prongs 1502, 1504, and 1506 projecting therefrom for reception in female connectors in the printed circuit board of the machine. In addition, there are two pairs of light connector prongs (not shown) one pair of which is associated with the indicator light 1508 shown in FIG. 19 and one which is associated with the second indicator light 1510 shown in FIG. 21. Preferably both lights are energized simultaneously to give better illumination under the translucent portion 1512 in the intermediate section 1514 of the switch body, such portion 1512 forming in effect a window exposed through the openings 1516 and 1518 as indicated in FIG. 20 aligned with the lights 1508 and 1510 when the parts are assembled. The intermediate section 1514 of the switch carries a bridging connector member 1520 which is adapted to bridge between either the pair of conductor prongs 1502 and 1504 or between the pair 1504 and 1506. The base 1500 of the switch remains in fixed position to the circuit board with the prong 1504 connected permanently to the strobe input of the SLC matrix and with the prong 1502 connected to the associated presidential candidate selection column and the prong 1506 connected to the associated

congressional candidate selection column. The intermediate portion 1514 of the switch is simply rotated 180° to select whether the prongs 1502 and 1504 will be bridged by depression of the switch or whether the prongs 1504 and 1506 will be bridged. The switch assembly is completed by a cover or cap 1522 as is indicated in FIGS. 22 and 23, the normal and depressed conditions being shown respectively in these Figures. It will be appreciated that only momentary depression of a switch is necessary to cause the associated candidate selection.

With reference to FIG. 4, a preferred embodiment of the invention utilizes a processing section 266 in accord with the principles indicated in FIG. 24. In FIG. 24, an input/output section is indicated by the reference character 1600 and will be seen to receive inputs at 1602 from the matrices of FIG. 4 and in particular from the switch matrix 260 thereof and to provide outputs at 1604 to the matrices, inclusive of the select and mode signals. The system also includes a central processing unit 1606 or arithmetic section, a read only memory 1608 and a random access memory 1610. The RAM, ROM, CPU, and I/O sections are provided with two-way street connections as at 1612, 1614, 1616 and 1618 to a main bus or two-way street system 1620 to achieve and accept the proper processing.

The CPU or arithmetic section 1606 is shown in greater block diagram detail in FIG. 25. This unit includes the accumulator 1622 which receives inputs from the switch matrix, the adder 1624, flip-flop 1626, RAM address 1628, ROM address 1630, SAVE address 1632 and the program counter 1634 operatively interconnected in the fashion indicated. The program counter 1634 is sequentially indexed, addressing ROM words which initiate instructions for the CPU. For example, a ROM word (BTS) will output the contents of the BU register section of the unit 1628 to the I/O section which latter decodes such information and stores it in output flip-flops. A ROM word (READ) will select, depending upon the word in the BU register section, four input lines and will store their data or states in the accumulator 1622. The process is a micro-computer which has a complete language of instruction and the processor can make branch decisions, can call subroutines, and can store and move data similar to a large computer. However, the control program is not alterable but is permanently encoded in the ROM so that the processor is a dedicated computer.

The system of FIGS. 24 and 25 can easily be accommodated on a MOS chip and such a system in conjunction with the SLC matrix is indicated in FIG. 26. In FIG. 26, the MOS chip is indicated by the reference character 1700 which includes an input interface section having a plurality of congressional candidate selection rows 1702, 1704, 1706, 1708, 1710, 1712, 1714 and 1716. This section also has a plurality of presidential candidate row indicated by reference characters 1718, 1720, 1722, 1724, 1726, 1728, 1730 and 1732.

The chip also has output interface sections one of which provides the strobes at the lines 1734, 1736, 1738, 1740, 1742, 1744 and 1746 and the other of which provides a wait mode strobe at the conductor 1748, eight select outputs at the lines 1750, 1752, 1754, 1756, 1758, 1760, 1762 and 1764. Additionally, this section provides the S or select mode output at the conductor 1766, the register or R mode output at the

conductor 1768 and the P clear output at the conductor 1770.

The voting point switch matrix portion is indicated generally by the reference character 1772 certain of which switches therein are shown associated with the presidential output rows while others are shown as associated with the congressional candidate output rows, as will be evident and in accord with the physical programming of the switches as previously described. The switch matrix also includes the voter exit switch 1780, the single category switch 1782, the voter entrance switch 1784 and the 2KEY switch 1786.

The switches 1774 and 1776 are power switches associated with the platen. The platen must be to the right in order to have power on to the machine. The custodian switch 1778 is in series with the power and must be closed in order to operate the machine.

As will be evident, the indicator lights are also in a matrix, the indicator light 1788 corresponding to the voting point switch 1790 and likewise, the counters are in a matrix, the counter 1792 also corresponding to the switch point 1790. Included in the indicator light matrix are the entrance lights 1794, the button stuck light 1796, the congressional candidate selection light 1798, the presidential candidate selection light 1800, all of which are located at the remote control unit or election official's control console and at the voting panel there is also provided the ready light 1802 and the voter exit or vote complete light 1804. The official control console also includes separate indicator lights of which the light 1806 indicates the a.c. current is on and of which the light 1808 indicates that the battery is operative. In addition to the aforementioned counters in the counting matrix, there is provided a presidential total counter 1810, a congressional candidate counter 1812 and a voter total counter 1814. As will be evident, the first six phases of the strobes interrogate the voting

point switch matrix and their corresponding light and counter matrices whereas the seventh phase is associated with the vote complete or exit switch 1780, the single category switch 1782, the instrumentalities 1802, 1810, 1812, 1804 and 1814 and with the voting official control console entity.

In the select mode when the signal is present at the conductor 1766, the Darlington 1820 is energized so that the various circuits can be completed in accordance with the strobes through the various Darlingtons 1822, 1824 and so on. In the register mode, when a signal appears at the conductor 1768, the Darlington 1826 is on so that the strobe can complete the circuits through the Darlingtons 1828, 1830 and so on. During the register mode, the signals appearing at the conductors 1750-1764 can only be in accord with a proper vote format as was described hereinabove. A signal appears at the P clear conductor 1770 at the end of a voting day in response to an official turning the 2KEY up to energize the Darlington 1832 which energizes solenoid 1833 which opens custodian switch 1778 to shut down the power to the machine.

FIG. 27 is a timing diagram showing the strobes, the select signals and the S mode signal and FIG. 28 is a timing diagram showing transition from the wait mode to the select mode and showing also a typical select mode cycle. In FIG. 28, from A to B denotes transition from the wait mode to the select mode, B to C denotes the first pass through the select mode and C to D denotes a typical select mode cycle.

FIGS. 29 illustrate the flow chart for the wait mode; FIGS. 30 indicate the flow chart for the select mode and FIGS. 31 illustrate the flow chart register mode and indicate the requisite logic and processing functions employed according to the preferred embodiment of the invention.

The following instructions apply to the flow charts:

Mnemonic	Name & Action	Description
Comp.	$\bar{A} \rightarrow A$	Complement of A into A
TAM	Test A equal M	Compares A to M
ATB	Skip if $A = M$	Ignore next instruction if $A = M$
	$A \rightarrow B$	Puts accumulator into lower 4 bits of B register
BTA	$A \rightarrow BL$ B to A	Puts the BL register into A
	$BL \rightarrow A$	$A \rightarrow (S_1-S_4)$ C $\rightarrow S$ mode
ATD 1	A to display	Outputs accumulator and C to the display data outputs
ATD 2		$A \rightarrow S_5-S_8$ C $\rightarrow R$ mode
LB Y,X	Load B $y \rightarrow BU$, $x \rightarrow BL$	Loads the B register. The upper two bits (BU) with y and lower 4 bits (BL) with x, where $y = 0, 1, 2, 3$ and $x = 0, 7, 8, 9, 10, 11$. A LB,y,x, immediately following a LB,y,x, is ignored.
SC	Set C	Sets the C flip-flop to 1
RSC	$1 \rightarrow C$	Resets the C flip-flop to 0
	Reset C	
TC	$0 \rightarrow C$	
	Test C	Tests C flip-flop and ignore next instruction if $C = 0$
SM, p	Skip if $C = 0$	Sets one bit of the contents of the RAM (M)
	Set M	$p = 1, 2, 4$, or 8
BTS	Set bit of M B to strobe	Outputs the lower 4 bits of the B register (B_4) to the specified strobe output. Resets other outputs
READ, a	Read keyboard $KB+A \rightarrow A$	Add the contents of the accumulator (A) to the keyboard return line information putting the result into A.
TKB	Test keyboard if key is up, then skip	Looks at keyboard return lines and if all keys are up, the next instruction is ignored. (A is not changed).
TIN	Test DIN if $DIN=1$, then skip	Looks at the discrete input (DIN) and if DIN is not zero, the next instruction is ignored.

Mnemonic	Name & Action	Description
ADD o,o	Add $M+A \rightarrow A$	Adds the output of the RAM (M) to the contents of the accumulator (A) putting the result into A
ADD, $1,o$	Add with carry $M+A+C \rightarrow A$ Carry $\rightarrow C$	Adds C flip-flop plus M plus A putting sum into A and puts the carry into C
RSM, p	Reset M	Resets one bit of the contents of the RAM (M) $p = 1,2,4$ or 8
TM, p	Reset bit of M Test M	Tests one bit of the contents of the RAM, ignore next instruction if bit= $p = 1,2,4,8$
TRA, O,x	Skip if bit of M = 0 Transfer to subroutine if $R=O$ $SU \rightarrow SU$, $PL+1 \rightarrow SL$ $O \rightarrow pU$, $x \rightarrow PL$ $1 \rightarrow R$ $R=1 \rightarrow PU$, $x \rightarrow PL$ $SU \rightarrow SU$, $SL \rightarrow SL$	Saves the present address of ROM plus one then transfers to block 0 (subroutine block) and sets subroutine flip-flop R.
TRA, $1,x$	Transfer if $R = 0$: $SU \rightarrow SU$, $PL+1 \rightarrow SL$ $SU \rightarrow PU$, $x \rightarrow PL$ if $R = 1$: $SU \rightarrow SU$, $SL \rightarrow SL$, $1 \rightarrow PU$, $x \rightarrow PL$	If in a main routine block, does a transfer to address in SU block.
RET, o	return $O \rightarrow R$, $SU \rightarrow PU$, $SL \rightarrow PL$	If in a subroutine block, does a transfer to address in block 1.
RET,1	return and skip $O \rightarrow R$, $SU \rightarrow PU$, $SL \rightarrow PL$	Resets R and puts save register into P register.
SSR, x	skip next instruction Set save register $x \rightarrow SU$	Same as RET, o and ignore the next instruction upon return.
ADD, $1,1$	Add with carry and skip $M+A+C \rightarrow A$ Carry $\rightarrow C$ Skip if $C = 0$	Puts x to upper 3 bits of S register SU $x = 0$ through 7
EXC, y,o	exchange $A \rightarrow M$, $BU \oplus y \rightarrow BU$	Same as ADD, 1 only the next ROM instruction is ignored if there is no carry
EXC, $y+1$	exchange and increment $A \rightarrow M$, $BU \oplus y \rightarrow BU$, $BL+1 \rightarrow BL$, Skip if $BL \rightarrow 8$	Exchanges the contents of the BU accumulator (A) with the contents of the RAM word being addressed. Then exclusive or the BU register with y, where $y = 0,1,2$, or 3
EXC, $y,-1$	exchange and decrement $A \rightarrow M$, $BU \oplus y \rightarrow BU$, $BL - 1 \rightarrow BL$, Skip if $BL \rightarrow 15$	Same as EXC, $y,0$ only the BL register is incremented after the next bit time. Ignore the next instruction if BL goes to 8.
LDA, y	Load accumulator from M	Same as EXC, $y,0$ only the BL register is decremented after the next bit time. Ignore the next instruction if BL goes to 15.
LAX, x	$M \rightarrow A$, $BU \oplus y \rightarrow BU$ Load accumulator from ROM $x \rightarrow A$	Puts the output of the RAM (M) into A, then exclusive or BU with y, where $y = 0,1,2$ or 3 x into accumulator A where $x = 0$ through 15
ADX, x	Add to accumulator $x + A \rightarrow A$ Skip if carry = 0	x plus A into A where $x = 0$ through 15 ignore next instruction if carry is zero

The RAM format is given in the following table:

RAM FORMAT

On an election day, the machine is taken out of its carrying case and physically set up whereafter the official unlocks the platen with the mechanical key lock on the main unit whereafter the platen may be cranked from the right to the left as viewed from the back of the machine. When the platen reaches the left side of the machine it automatically locks in this position and closes a power switch which applies power to the entire machine. During the time that the platen is being cranked to the left, a proof sheet is printed to verify the 10 positions of the counters at this time. The voting official turns the 2KEY on the remote control unit or console to the "down" position to enable the entrance switch and the machine is now ready for voting. Normally, the 2KEY is placed in an envelope and the number on the outside protective counter is recorded on 15 this envelope.

Whenever the machine is powered up, it goes into a nonvote operation. The exit and candidate buttons are inoperative and pressing a button on the main unit will 20 result in a "button stuck" light turning on at the remote control. The "exit" or vote complete light does come on when the machine is powered up but no other lights will be on. Entrance is given by momentary depression of the entrance switch at the remote control console and this allows the voter to operate the main unit and also illuminates the entrance on the remote control unit and the ready or commence light on the main unit. A voter may then make two selections, a presidential candidate selection and a congressional candidate selection or, alternatively, if the single category status switch is in the "single category" position, all voting points are treated as if they were presidential candidates and the voter may make only a single selection. As a voting point switch is momentarily depressed, it becomes illuminated to indicate that a selection has been made for that office. As soon as the voter has made a selection for either office, the "ready" or commence light on the main unit extinguishes.

Assuming that the selections have been made properly, a voter now may push the exit button which illuminates the vote complete light and the respective counters count while a buzzer in the main unit sounds off for approximately 1 second. After approximately 10 seconds, the "vote complete" indicator goes out.

When the single category switch is closed, the voter can exit after making only one selection. All selections, regardless of the candidate button orientation, are recognized as a presidential selection and the congressional light on the remote control unit is not activated in this type of election. All other lights function normally. The lighted entrance button on the remote control unit and the ready light at the main unit go out after a single selection and the congressional totalizer is not activated in the single category election.

What is claimed is:

1. In an automatic voting machine having a vote selection panel providing a plurality of voting points, the combination of:

a plurality of normally open switches defining a 60 switch matrix having a plurality of input lines and a plurality of output lines, certain of said switches being located at said voting points and constituting vote selection switches, another of said switches being located remote from said vote selection panel and constituting a vote enabling switch, and a further one of said switches being associated with said voting panel and constituting a voter exit switch;

a plurality of normally inactive indicators defining an indicator matrix having a plurality of first input lines and a plurality of second input lines, one of said indicators being associated with each of said voting points;

a plurality of normally inactive counters defining a counter matrix having a plurality of first input lines and a plurality of second input lines, one of said counters being associated with each of said voting points;

clock means having a plurality of output lines connected to the input lines of said switch matrix and to said first input lines of said indicator matrix and of said counter matrix for sequentially and cyclically activating such input lines; and

logic means connected to the output lines of said switch matrix for cyclically and sequentially activating said second input lines of said indicator matrix in response to actuation of said vote enabling switch and in accord with a pattern of vote selection switches selectively actuated by a voter subsequent to the actuation of said vote enabling switch to activate those indicators corresponding to the voter-selected vote selection switches and for sequentially activating said second input lines of said counter matrix in accord with said pattern in response to actuation of said voter exit switch to activate those counters corresponding to the voter-selected vote selection switches.

2. In an automatic voting machine as defined in claim 1 wherein said logic means includes N OF M logic means for limiting said activation of the indicators and counters to a format of permissible voting.

3. In an automatic voting machine as defined in claim 2 wherein said logic means also includes means for preventing activation of said counters in the event of undervoting.

4. In an automatic voting machine as defined in claim 1 wherein said logic means includes means for preventing activation of said counters in the event of undervoting.

5. In an automatic voting machine having a vote selection panel providing a plurality of voting points, the combination of:

a plurality of normally open switches defining a switch matrix having a plurality of input lines and a plurality of output lines, certain of said switches being located at said voting points and constituting vote selection switches, another of said switches being located remote from said vote selection panel and constituting a vote enabling switch, and a further of one of said switches being associated with said voting panel and constituting a voter exit switch;

a plurality of indicators defining an indicator matrix having a plurality of first input lines and a plurality of second input lines, one of said indicators being associated with each of said voting points;

a plurality of counters defining a counter matrix having a plurality of first input lines and a plurality of second input lines, one of said counters being associated with each of said voting points;

clock means having a plurality of output lines connected to the input lines of said switch matrix and to said first input lines of said indicator matrix and of said counter matrix for sequentially and cyclically activating such input lines; and

logic means connected between said output lines of

said switch matrix and said second input lines of said indicator matrix and of said counter matrix responding to actuation of said vote enable switch to produce cyclically repetitive strobe pulse trains at said second input lines of said indicator matrix in consonance with a program of vote selection switch actuations made subsequent to said actuation of the vote enable switch and responding to subsequent actuation of the voter exit switch to apply such strobe pulse train to said second input lines of said counter means.

6. In an automatic voting machine as defined in claim 5 wherein said logic means includes N of M logic means for limiting said strobe pulse trains to a format of permissible voting.

7. In an automatic voting machine as defined in claim 6 wherein said logic means also includes means for preventing transfer of said strobe pulse trains to said counter means in the event of undervoting.

8. In an automatic voting machine as defined in claim 5 wherein said logic means includes means for preventing transfer of said strobe pulse trains to said counter means in the event of undervoting.

9. In an electronic voting machine having a vote selection panel presenting a plurality of voting points, the combination of:

circuit means having a plurality of input terminals, a plurality of output terminals and a plurality of normally open switches connecting said input and output terminals, said switches being associated with said voting points;

clock means connected to said input terminals for cyclically and sequentially interrogating said input terminals;

counter means associated with each of said voting points for tallying votes selected for candidates associated with such voting points; and

N of M logic means connected to said output terminals for actuating those counter means corresponding to voted voting points after completion of N of M voting selection.

10. In an electronic voting machine as defined in claim 9 wherein said output lines are arranged in pairs and each switch is positionally adjusted to connect between an associated input line and either one of an associated pair of outlet lines.

11. In an electronic voting machine as defined in claim 10 wherein said N or M logic means comprises first means connected with one outlet line of each of said pairs and second means connected with the other outlet line of each of said pairs whereby separate logic functions can be performed for the two sets of outlet lines.

12. In an electronic voting machine as defined in claim 9 including indicator means associated with each of said voting points; and one of said normally open switches controlling said logic means to actuate said indicator means and another of said normally open switches controlling said logic means to actuate said counter means.

13. In an electronic voting machine as defined in claim 12 wherein said output lines are arranged in pairs and each switch is positionally adjusted to connect between an associated input line and either one of an associated pair of outlet lines.

14. In an electronic voting machine as defined in claim 13 wherein said N of M logic means comprises

first means connected with one outlet line of each of said pairs and second means connected with the other outlet line of each of said pairs whereby separate logic functions can be performed for the two sets of outlet lines.

15. In an electronic voting machine having a vote selection panel presenting a plurality of voting points, the combination of:

a normally open switch associated with each of said voting points, each switch having an input terminal and an output terminal;

circuit means connected to the terminals of said switches for presenting a plurality of input lines each connected to a number of said input terminals and a plurality of output lines each connected to a number of said output terminals;

clock means for cyclically and sequentially interrogating said input lines;

counter means associated with each of said voting points; and

logic means connected to said output lines for actuating those counter means associated with voted voting points upon completion of a voting operation.

16. In an electronic voting machine as defined in claim 15 wherein said output lines are arranged in pairs and each switch is positionally adjusted to connect between an associated input line and either one of an associated pair of outlet lines.

17. In an electronic voting machine as defined in claim 16 wherein said logic means comprises first means connected with one outlet line of each of said pairs and second means connected with the other outlet line of each of said pairs whereby separate logic functions can be performed for the two sets of outlet lines.

18. In an electronic voting machine as defined in claim 15 including indicator means associated with each of said voting points; and one of said normally open switches controlling said logic means to actuate said indicator means and another of said normally open switches controlling said logic means to actuate said counter means.

19. In an electronic voting machine as defined in claim 18 wherein said output lines are arranged in pairs and each switch is positionally adjusted to connect between an associated input line and either one of an associated pair of outlet lines.

20. In an electronic voting machine as defined in claim 19 wherein said logic means comprises first means connected with one outlet line of each of said pairs and second means connected with the other outlet line of each of said pairs whereby separate logic functions can be performed for the two sets of outlet lines.

21. In an electronic voting machine having a vote selection panel presenting a plurality of voting points, the combination of:

a vote selection switch associated with each of said voting points;

a counter associated with each of said switches; circuit means connecting pluralities of switches forming columns into a plurality of rows and including at least two output terminals for each of said rows;

clock means for cyclically and sequentially interrogating said columns of switches, each of said switches being positionally adjustable for produc-

ing an output at a selected one of said two terminals of its corresponding row;
first N of M logic means connecting one of each said two terminals to said counters for registering N of M possible selections of one group of said switches; 5

second N of M logic means connecting the other of each of said two terminals to said counters for registering N of M possible selections of another group of said switches.

22. In an electronic voting machine as defined in claim 21 including an indicator associated with each of said voting points, vote enable switch means connected to said circuit means for controlling said first and second logic means to actuate said indicators in accord with voter selections, and voter exit switch means connected to said circuit means for controlling said first and second logic means to actuate said counters in accord with said voter selections. 10

23. In an electronic voting machine as defined in claim 22 wherein each of said logic means includes means for preventing actuation of said counters until N of M selections has been made. 20

24. In an electronic voting machine having a vote selection panel presenting a plurality of voting points, the combination of: 25

circuit means for presenting a plurality of input lines and a plurality of pairs of output lines; a normally open switch module associated with each of said voting points, each switch module having an input terminal and an output terminal, said switch modules being arranged in groups each associated with a different one of said input lines with all of the input terminals of each group being connected to the associated input line, each of such individual switch module being positionable to connect its output terminal with either of the output lines of the associated pair thereof;

counter means associated with each voting point for tallying votes selected for candidates associated with such voting points; 40

clock means connected to said input lines for interrogating said voting points; and

logic means connected to said pairs of output lines for actuating those counter means associated with voted voting points upon completion of a voting operation. 45

25. In an electronic voting machine as defined in claim 24 including indicator means associated with each voting point for indicating a voter selection at such voting point; a normally open vote enable switch connected between an input line and an output line at a position unoccupied by any other switch, said logic means being responsive to actuation of said vote enable switch to actuate those indicator means associated with voting points later selected by the voter; a normally open voter exit switch connected between an input line and an output line at a position unoccupied by any other switch, said logic means being responsive to actuate said counter means subsequent to actuation of said voter exit switch. 50

26. An electronic voting machine system comprising, in combination:

a vote selection panel presenting a plurality of voting points; 65

a vote selection switch associated with each of said voting points;

a voter exit switch associated with said panel;

indicator means associated with each of said voting points for indicating voter selections;

counter means associated with each of said voting points for tallying votes cast for the candidate associated with each such voting point;

a voting official's console including a voter entrance switch;

each of said switches having an input terminal and an output terminal and all of said switches being interconnected to form a matrix having a plurality of input lines and a plurality of output lines; clock means for sequentially interrogating said input lines; and

logic means connected to said output lines for actuating said indicator means in response to actuation of said voter entrance switch and subsequent actuation of vote selection switches and for actuating said counters in response to actuation of said voter exit switch to tally the voter selections. 10

27. In an electronic voting machine having a vote selection panel presenting a plurality of voting points, the combination of:

a normally open vote selection switch associated with each voting point;

a vote selection indicator associated with each voting point;

counter means associated with each voting point;

a voter exit switch having an input terminal and an output terminal;

matrix circuit means presenting a plurality of input lines and a plurality of output lines;

the input terminals of a group of said vote selection switches being connected to each input line and the input terminal of said voter exit switch being connected to one of said input lines, the output terminals of each of the vote selection switches of each group being connected to a different one of said output lines and the output terminal of said voter exit switch being connected to one of said output lines;

the voter selection indicators and the counter means associated with each group of vote selection switches being connected to the input line associated with that group; and

logic means connected to said output lines and having a number of control lines equal to the number of said output lines for producing signals in consonance with and in response to momentary actuation of said voting point switches and of said voter exit switch, said logic means including N of M logic means actuating said indicators in accord with said signals produced in accord with actuation of said voting point switches and for switching over to corresponding actuation of said counter means in response to closing of said voter exit switch. 30

28. In an automatic voting machine as defined in claim 1 wherein said indicators are low voltage lamps and said lamps are strobed at a voltage level appreciably greater than said low voltage. 45

29. In an automatic voting machine having a vote selection panel providing a plurality of voting points, the combination of:

a plurality of normally open switches defining a switch matrix having a plurality of input lines and a plurality of output lines, certain of said switches being located at said voting points and constituting vote selection switches, another of said switches being located remote from said vote selection

panel and constituting a vote enabling switch, and a further one of said switches being associated with said voting panel and constituting a voter exit switch;

a plurality of indicators defining an indicator matrix having a plurality of first input lines and a plurality of second input lines, one of said indicators being associated with each of said voting points;

clock means having a plurality of output lines connected to the input lines of said switch matrix and to said first input lines of said indicator matrix for sequentially and cyclically activating such input lines;

logic means connected to the output lines of said switch matrix for cyclically and sequentially activating said second input lines of said indicator matrix in response to actuation of said vote enabling switch and in accord with a permissible pattern of vote selection switches actuated subsequent to the actuation of said vote enabling switch; and counter means connected to said logic means for tallying the votes selected by the voter in response to actuation of said voter exit switch.

30. In an automatic voting machine as defined in claim 29 wherein said logic means includes N of M logic means for limiting actuation of the indicators and counter means to a format of permissible voting.

31. In an automatic voting machine as defined in claim 30 wherein said logic means also includes means for preventing actuation of said counter means in the event of undervoting.

32. In an automatic voting machine as defined in claim 29 wherein said logic means includes means for preventing actuation of said counter means in the event of undervoting.

33. In an automatic voting machine having a vote selection panel providing a plurality of voting points, the combination of:

a plurality of normally open switches defining a switch matrix having a plurality of input lines and a plurality of output lines, certain of said switches being located at said voting points and constituting vote selection switches, another of said switches being located remote from said vote selection panel and constituting a vote enabling switch, and a further one of said switches being associated with said voting panel and constituting a voter exit switch;

a plurality of indicators defining an indicator matrix having a plurality of first input lines and a plurality of second input lines, one of said indicators being associated with each of said voting points;

a plurality of counters defining a counter matrix having a plurality of first input lines and a plurality of second input lines, at least one of said counters being associated with each of said voting points;

clock means having a plurality of output lines connected to the input lines of said switch matrix for sequentially and cyclically interrogating such input lines;

counter means for tallying the individual votes cast for candidates corresponding to said voting points; and

logic means connected to said output lines of said switch matrix and to said counter means and responding respectively to actuation first of said vote enable switch and to later actuation of said voter exit switch first accumulating information in conso-

nance with a program of vote selection switch actuations made subsequent to said actuation of the vote enable switch but prior to said actuation of the voter exit switch and later actuating said counter means in accord with such information.

34. In an automatic voting machine as defined in claim 33 wherein said logic means includes N of M logic means for limiting said information to a format of permissible voting.

10 35. In an automatic voting machine as defined in claim 34 wherein said logic means also includes means for preventing actuation of said counter means in the event of undervoting.

15 36. In an automatic voting machine as defined in claim 34 wherein said logic means includes means for preventing actuation of said counter means in the event of undervoting.

20 37. In an electronic voting machine having a vote selection panel defining a plurality of voting points, the combination of:

a plurality of switches defining a switch matrix having a plurality r of input lines and a plurality s of output lines, certain of said switches being located at said voting points and constituting vote selection switches, another of said switches being located remote from said voting panel and constituting a vote enabling switch, and a further one of said switches being associated with said voting panel and constituting a voter exit switch;

25 clock means connected to said input lines and having r nonoverlapping phases for interrogating said input lines in sequential and cyclic fashion;

30 logic means connected to said output lines for accumulating vote selection information in consonance with voter selection and actuation of said vote selection switches after actuation of said vote enabling switch, said logic means having s output lines;

35 40 a plurality of counters corresponding in number to the number of voting points and defining a counter matrix having r first input lines and s second input lines; and

45 40 said logic means having its output lines connected to said second input lines of said counter matrix for actuating those counters corresponding with the information accumulated during vote selection in response to actuation of said voter exit switch.

38. In an automatic voting machine as defined in claim 37 wherein said logic means includes N of M logic means for limiting accumulated information to a format of permissible voting.

50 39. In an automatic voting machine as defined in claim 38 wherein said logic means also includes means for preventing actuation of said counters in the event of undervoting.

55 40. In an automatic voting machine as defined in claim 37 wherein said logic means includes means for preventing actuation of said counters in the event of undervoting.

60 41. In an automatic voting machine having a voting panel defining a plurality of voting points, the combination of:

65 a plurality of switches defining a switch matrix having a plurality r of input lines and a plurality s of output lines, certain of said switches being located at said voting points and constituting vote selection switches, certain others of said switches being con-

nected to one input line to which none of said vote selection switches are connected; clock means connected to said input lines and having r non-overlapping phases for sequentially and cyclically interrogating said input lines with said one input line being interrogated after all input lines having vote selection switches connected thereto are interrogated; logic means connected to said output lines for accumulating voting information effected by voter actuation of said vote selection switches and having s output lines at which such information cyclically and sequentially appears; counter means for tallying individual votes cast for those voting points corresponding to the information accumulated by said logic means; voter exit means responsive to actuation of one of said certain other switches for connecting said output lines of said logic means to said counter means and resetting said logic means after one cycle of accumulated information appears at the output lines of the logic means when so connected.

42. In a voting machine as defined in claim 41 wherein said counter means comprises a plurality of counters defining a matrix having a $r-1$ first input lines and s output lines, there being one counter for each voting point in such matrix, said output lines of the logic means being connected to said second input lines of the counter matrix when said voter exit means is actuated, and said first input lines of the counter matrix being cyclically and sequentially activated in consonance with interrogation of the corresponding input lines of said switch matrix.

43. In a voting machine as defined in claim 42 wherein said logic means includes N of M logic means for limiting the accumulated information to a permissible voting format.

44. In a voting machine as defined in claim 43 wherein said logic means also includes means for preventing actuation of said counter means in the event of undervoting.

45. In a voting machine as defined in claim 41 wherein said logic means includes N of M logic means for limiting the accumulated information to a permissible voting format.

46. In a voting machine as defined in claim 45 wherein said logic means also includes means for preventing actuation of said counter means in the event of undervoting.

47. In a voting machine as defined in claim 41 wherein said logic means includes means for preventing actuation of said counter means in the event of undervoting.

48. In a voting machine as defined in claim 41 including a plurality of indicators defining an indicator matrix having $r-1$ first input lines and s second input lines, there being one indicator of such indicator matrix located at each voting point and said indicators being connected between the first and second input lines in accord with the corresponding vote selection switches, said first input lines being connected to said clock means for simultaneous activation with the interrogation of said input lines of the switch matrix; and means responsive to another of said certain other switches for readying said logic means for information accumulation and for connecting said output lines of the logic means to said second input lines of said indicator matrix.

49. In a voting machine as defined in claim 48 wherein said counter means comprises a plurality of counters defining a matrix having $r-1$ first input lines and s output lines, there being one counter for each voting point in such matrix, said output lines of the logic means being connected to said second input lines of the counter matrix when said voter exit means is actuated, and said first input lines of the counter matrix being cyclically and sequentially activated in consonance with interrogation of the corresponding input lines of said switch matrix.

50. In a voting machine as defined in claim 49 wherein said logic means includes N of M logic means for limiting the accumulated information to a permissible voting format.

51. In a voting machine as defined in claim 50 wherein said logic means also includes means for preventing actuation of said counter means for preventing actuation of said counter means in the event of undervoting.

52. An electronic voting machine system comprising, in combination:

a voting panel having a plurality of voting points; a control panel having at least one control point; a voting machine with which said voting panel is associated and including at least one security point; a switch matrix having input columns and output rows, said switch matrix containing a switch for each voting point, a switch for said control point and a switch for said security point; a counter matrix having input columns and input rows and including a counter for each voting point; and

processor means for actuating individual counters of said counter matrix in accord with and in response to proper voting conditions and completion of proper vote input at said switch matrix, said processor means including means for strobing said input columns of said switch matrix and of said counter matrix, means connected to said output rows of said switch matrix for producing corresponding row output signals in response to said proper voting conditions and completion of proper vote input, said row output signals being connected to said input rows of said counter matrix.

53. In an electronic voting machine, in combination:

a voting panel having a plurality of voting points; a switch at each of said voting points; and electric circuit means connecting the switches at said voting points as a cross point matrix having n rows and m columns;

each switch being physically movable at its voting point for programmable connection between a single column and a selected one of at least two rows whereby there are at least two rows of said electric circuit means available for each row of switches.

54. In an electronic voting machine as defined in claim 53 including means for interrogating said columns sequentially in time.

55. In an electronic voting machine as defined in claim 54 including first logic function means connected to certain of said m rows and second logic function means connected to others of said m rows.

56. In an electronic voting machine, in combination: a voting panel having a plurality of voting points and a voting switch associated with each voting point, each switch being momentarily actuatable by a voter

to indicate voter preference for a candidate associated with each voting point;
 electric circuit means connecting said switches in cross point matrix form wherein each cross point is completed momentarily by switch actuation as 5 aforesaid;
 means for sequentially and repetitively interrogating columns of said cross point matrix; and logic means connected to rows of said cross point matrix for responding to interrogation signals 10 passed by said momentary actuation of said switches.

57. In an electronic voting machine as defined in claim 56 wherein each switch is physically movable at its voting point between at least two program positions 15 for connection to a selected one of at least two rows.

58. In an electronic voting machine, in combination:

a voting panel having a plurality of voting points; a voting switch associated with each voting point; electrical circuit means connected to the switches of said voting points for providing a cross point matrix system in which individual cross points thereof are completed by actuation of individual voting 25 switches; means for interrogating columns of said matrix and logic means connected to rows of said matrix for responding to interrogation signals passed by completion of individual cross points to effect tabulation of a proper vote.

59. In an electronic voting machine as defined in claim 58 wherein said logic means includes a processor and a read only memory and which accepts row inputs and produces outputs in accord with instructions encoded in said read only memory.

60. In an electronic voting machine as defined in claim 58 wherein said logic means includes an input-/output section, a processor section, a random access memory and a read only memory, which accepts row inputs at said input/output section and produces outputs in accord with instructions encoded in said read only memory.

61. In an election voting machine, in combination: a switch matrix having a plurality of input lines and a plurality of output lines corresponding to rows and columns of the matrix, said switch matrix comprising a plurality of voting point switches and a plurality of other switches, said other switches including security switches actuatable in response only to proper set-up of the voting machine; and logic means for cyclically strobing said input lines and for processing data received from said output lines to determine its propriety within the framework of a selected ballot format.

62. In an electronic voting machine as defined in claim 61 wherein said other switches also include a voting official-controlled switch giving a voter entrance to the machine and a voter-controlled switch giving exit 60 from the machine.

63. In an electronic voting machine, in combination: a switch matrix having a plurality of input lines and a plurality of output lines corresponding to rows and columns of the matrix, said matrix including at

least a plurality of voting point switches at which candidate selections may be made by a voter; a vote counting matrix corresponding to said voting point switches and including discrete vote recording means connected to provide two sets of input lines corresponding respectively to the input lines and output lines of said switch matrix with which said voting point switches are associated; logic means cyclically strobing said input lines of the switch matrix and for processing data received from said output lines to determine its propriety within the framework of a selected ballot format; and means for causing said logic means selectively to strobe said sets of said input lines of said vote counting matrix in accord with the data processed from said switch matrix whereby to record a voter's selection.

64. In an electronic voting machine as defined in claim 63 wherein the means last mentioned includes a switch in said switch matrix.

65. In an electronic voting machine as defined in claim 64 wherein said switch matrix includes further switches which allow recordation of a voter's selection only in response to proper set-up and functioning of said machine.

66. In an electronic voting machine as defined in claim 65 wherein said logic means includes a processor and a read only memory and which accepts row inputs and produces outputs in accord with instructions encoded in said read only memory.

67. In an electronic voting machine as defined in claim 65 wherein said logic means includes an input-/output section, a processor section, a random access memory and a read only memory, which accepts row inputs at said input/output section and produces outputs in accord with instructions encoded in said read only memory.

68. In an electronic voting machine as defined in claim 67 wherein each switch is physically movable at its voting point between at least two program positions for connection to a selected one of at least two rows.

69. In an electronic voting machine as defined in claim 63 wherein said switch matrix includes further switches which allow recordation of a voter's selection only in response to proper set-up and functioning of said machine.

70. In an electronic voting machine as defined in claim 69 wherein said logic means includes a processor and a read only memory and which accepts row inputs and produces outputs in accord with instructions encoded in said read only memory.

71. In an electronic voting machine as defined in claim 69 wherein said logic means includes an input-/output section, a processor section, a random access memory and a read only memory, which accepts row inputs at said input/output section and produces outputs in accord with instructions encoded in said read only memory.

72. In an electronic voting machine as defined in claim 71 wherein each switch is physically movable at its voting point between at least two program positions for connection to a selected one of at least two rows.

UNITED STATES PATENT OFFICE
CERTIFICATE OF CORRECTION

Patent No. 3,847,345

Dated November 12, 1974

Inventor(s) Michael T. Moldovan, Jr.; Charles J. Lindros; Lawrence L. Anderson; Robert D. Wescott and Richard J. Cusimano
It is certified that error appears in the above-identified patent and that said Letters Patent are hereby corrected as shown below:

Column 1, line 32, change "of" to ---for---.

Column 4, line 28, after semicolon (;) delete "y LB,y,x".

Column 10, line 18, change "electrion" to ---election---.

Column 12, line 11, change "Likeiwse" to ---Likewise---.

Column 14, line 11, change "thee" to ---the---.

Column 16, line 19, change "iputs" to ---inputs---.

Column 21, line 66, change "of" to ---to---.

Column 23, line 31, before "the" insert ---that---.

Column 29, claim 10, line 44, change "connected" to ---connect---.

Column 29, claim 11, line 49, change "N or M" to ---N of M---.

Column 34, claim 37, line 19, change "votinG" to ---voting---.
